UNITED STATES PATENT OFFICE

MORGAN R. BUTLER, OF WAUKESHA, WISCONSIN

MATERIAL HANDLING EQUIPMENT

Application filed January 19, 1929. Serial No. 333,680.

This invention relates to certain new and useful improvements in material handling devices and refers more particularly to measuring hoppers and their discharge gates.

The gates of such hoppers are usually held in closed position by a suitable latch mechanism so that when the latch is tripped the weight of the material within the hopper opens the gate and heretofore it has been customary to manually return the gate to closed position by means of a pulley and cable. This method has numerous objections and therefore, it is an object of this invention to provide means associated with a hopper of the character described whereby its discharge gate is opened and closed by gravity.

Another object of this invention resides in the provision of a hopper of the character described having a gate structure closing its outlet, and which is positively held in open or closed position by a releasable latch.

Another object of this invention resides in the provision of a hopper of the character described having a pivoted gate structure closing its discharge opening, which is at all times urged to closed position by gravity, and which is positively held in open position by a suitable latch, which when tripped after the discharge of material permits the return of the gate structure to closed position.

A further object of this invention resides in the provision of a device of the character described having a pair of hoppers, each equipped with a hinged gate structure movable to and from closed position by gravity, the movements of which are controlled from a common control which permits the opening or closing of one gate structure without effecting the other.

And a still further object of this invention resides in the provision of means for yieldably maintaining the common control for the gate structures of the pair of hoppers in neutral position.

With the above and other objects in view which will appear as the description proceeds, my invention resides in the novel construction, combination and arrangement of parts substantially as hereinafter described and more particularly defined by the append-

ed claims, it being understood that such changes in the precise embodiment of the herein disclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is an elevational view of a pair of measuring hoppers embodying my invention and illustrating a portion of the bin from which they are supported;

Figure 2 is a perspective view of the gate structures and their associated latch and latch release mechanism;

Figure 3 is a view similar to Figure 2 illustrating a slightly modified manner of maintaining the common control for both gate structures in neutral position.

Referring now more particularly to the accompanying drawings in which like numerals designate like parts throughout the several views, 5 represents a bin which is divided into compartments 6 and 7 by a partition 8, the compartments discharging their respective contents through chutes 9 normally closed by gates 10, the compartment 6 having two discharge chutes and the compartment 7, one. The bin 5 is suitably supported from a fabricated framework, a portion of which is illustrated, as at 11, sufficiently high to permit trucks or other vehicles to be driven beneath measuring hoppers 12 and 13 supported from the bin, by rods 14 or the like.

The hoppers are rigidly connected to form a unitary structure by forming their sides of a single plate, and are mounted directly beneath the discharge chutes 9, being arranged so that the hopper 12 receives material from the bin compartment 6, and the hopper 13 from the compartment 7. The lower portions of the hoppers converge and terminate in outlet openings, each of which is adapted to be closed by a gate structure 16, and as the construction of both gates is identical the description of one will suffice for both.

Each gate structure 16 consists of a gate

proper 17 of a size to cover the entire outlet opening of its respective hopper, and which is secured, by welding or any other suitable manner, to a pair of spaced bars 18 which extend outwardly thereof to hingedly mount the structure, as at 19, from supporting members 20, welded or otherwise fixed, to the adjacent wall of the respective hopper. The outer ends of the spaced bars 18 have a weight 21 fixed thereto and are further connected at their extreme outer ends by an inverted U shaped member 22, the lower ends of whose arms are cut off at an angle and connected by a plate 23 which is welded or otherwise fixed thereto. The weight 21 is sufficient to maintain the gate structure closed when its hopper is empty, and to prevent the opening of the gate when the hopper is filled with material a latch 24 is provided.

The latch 24 is pivotally mounted at its upper end as at 25 between a pair of angle plates 26 secured to the adjacent wall of the hopper. The inner edge of the latch is cut away at its outer free end to provide a stop 27 which engages the U shaped member 22 when the gate structure is in closed position and secures the same in said position, the latch 24 being moved to active position by gravity. When it is desired to open the gate, the latch 24 is moved out of engagement with the member 22 by means of a latch release lever 28 fixed to a transverse shaft 29, see Figure 2, and connected at its outer free end with the latch 24 by means of a chain 30 or the like.

The transverse shaft 29 is journaled in bearings 31 suitably carried by bracket members 32 fixed to the adjacent portion of the hopper and has one end extended and directed upwardly to provide a control lever 33. Thus it will be seen that as the shaft 29 is turned by means of its lever 33 the latch 24 may be moved out of engagement with the U shaped member 22 to permit the gate to be opened by the weight of the material within the hopper.

As the gate moves to its full open position illustrated in dotted lines in Figure 1, the plate 23 connecting the lower ends of the arms of the inverted U shaped member 22 is aligned with a second stop 34 formed on the latch member at a point spaced inwardly from the stop 27, which, by reason of the fact that the latch is at all times urged by gravity toward the gate structure, engages the plate 23, as illustrated in dotted lines in Figure 1, to secure the gate structure in open position, the lever 33 having been released to permit said movement of the latch 24. The gate structure is thus maintained in its open position until the lever 33 is again actuated to trip the latch 24 releasing the gate, and permitting it to be moved by its weight 21 to closed position where it is again locked by

the action of the latch 24 in the manner hereinbefore described.

The control of both gates is simplified by connecting the levers 33 thereof by means of a chain 35, so that movement of either lever 33 in one direction trips one latch, and movement of the same lever in an opposite direction trips the other latch. To insure the levers 35, and consequently the latch release, levers 28 maintaining a neutral position when not in use, and to maintain the chain taut, balanced weights 36 are extended outwardly from the levers 33.

It is to be understood that a suitable platform (not shown) is provided for the operator, which is carried by the supporting structure of the bin and is so positioned as to permit ready access to the control levers 33 and to the controls 37 of the several bin gates 10.

Figure 3 illustrates a slightly modified manner of connecting or interlocking the levers 33 of the two latch release devices, which consists of a bar or rod 38 slidably mounted in plates 39, adapted to be fixed to the hoppers, and whose out-turned ends 40 engage opposite sides of the levers 33, the levers 33 being maintained in engagement with the ends 40 by the weight of their release levers 28. A handle 41 is provided for actuating the bar 38 and contractile springs 42 having one end fixed to the bar, as at 43, and having their other ends fixed to clips 44 suitably secured to the walls of the hoppers provide means for yieldably maintaining the bar 38 in a neutral position.

From the foregoing description taken in connection with the accompanying drawings, it will be readily apparent to those skilled in the art to which an invention of the character described appertains that I provide a novel gate structure for hoppers of the character described in which the gate is actuated to and from closed position by gravity, is positively held in open position, and in which the movements of different gate structures may be independently controlled from a common means.

What I claim as my invention is:

1. The combination with a material handling hopper having an outlet opening adapted to be closed by a gate structure movable to and from closed position, of means tending at all times to close the gate structure, and a single means mounted from a substantially fixed structure engageable with the gate structure for holding the same in either closed or open position.

2. The combination with a material handling hopper having an outlet opening adapted to be closed by a gate movable from closed position by the weight of the material, gravity actuated means for returning the gate to closed position, and a single readily releasable means mounted from a substantially

fixed structure for holding the gate in either position.

3. In a device of the character described, including a material handling hopper having an outlet opening adapted to be closed by a gate structure movable to and from closed position, means at all times tending to move the gate structure to closed position, a latch member mounted from a substantially fixed structure and engageable with the gate structure for holding it in either closed or open position, and means for disengaging the latch member from the gate structure to release the same for movement from either position, said release of the gate structure when in closed position permitting the weight of the material to move it to its open position and when in open position permitting said first-mentioned means to move the gate structure to closed position.

4. In a device of the character described, including material handling hoppers having outlet openings, gate structures adapted to close said openings and movable to and from closed position by gravity, means controlling the movement of said gate structures whereby movement of said means in one direction effects the opening or closing of one gate structure and movement in the opposite direction effects the opening or closing of another gate structure.

5. In a device of the character described, including material handling hoppers having outlet openings, gate structures adapted to close said openings and movable to and from closed position, means at all times tending to move the gate structures to closed position, latch members engageable with the gate structures for holding them in either closed or open position, and common means for releasing said latch members independent of each other, the release of a latch member when its respective gate structure is in closed position permitting the weight of material thereabove to move it to its open position and when in open position permitting its said first mentioned means to move the gate structure to closed position.

6. In a device of the character described, including material handling hoppers having outlet openings, gate structures adapted to close said openings and movable to and from closed position by gravity, latches for holding the gate structures in either closed or open position, latch release means for each gate structure, means interlocking the latch release means, and means connecting each latch release means with its respective latch whereby one latch may be released upon actuation of the interlocked latch release means without effecting any other latch.

7. In a device of the character described, including material handling hoppers having outlet openings, gate structures adapted to close said openings and movable to and from

closed position by gravity, latches for holding the gate structures in either closed or open position, means for releasing each latch, means connecting said latch release means, and means normally maintaining the connected latch release means in neutral position.

8. The combination with a material handling hopper having an outlet opening adapted to be closed by a gate structure movable to and from closed position, of a single latch member mounted at one side of the gate structure and engageable with a portion of the gate structure in either of its positions to readily releasably hold the same in either position, and said latch member being readily disengaged from the lock structure to free the same from either position.

9. The combination with a material handling hopper having an outlet opening adapted to be closed by a gate structure movable to and from closed position, of a latch member having spaced stops one of which engages the gate structure when in closed position and the other when in open position, and said latch member being readily releasable to free the gate structure for movement from either position.

10. The combination with a material handling hopper having an outlet opening adapted to be closed by a gate structure movable from closed position by the weight of the material, of gravity actuated means for moving the gate structure to closed position, and a latch member engageable with the gate structure in either closed or open position to readily releasably hold the gate structure in either position.

11. The combination with a material handling hopper having an outlet opening adapted to be closed by a gate structure movable from closed position by the weight of the material, of gravity actuated means for returning the gate structure to closed position, a latch member maintained in operative position by gravity, and spaced abutments carried by the latch member, one of which is engageable with the gate structure when in closed position and the other when in open position, whereby the latch member releasably holds the gate structure in either of its positions.

12. The combination with a material handling hopper having an outlet opening, of a gate structure for closing the opening, means pivotally mounting the gate structure, a pivoted latch member, an abutment carried by the latch member and engaging the gate structure to hold the same in closed position, said latch member being releasably maintained in operative position by gravity, release of the latch member freeing the gate structure for movement to open position by the weight of the material, a second abutment carried by the latch member engageable with

the gate structure when in open position to releasably maintain the same in said position, and gravity actuated means for returning the gate structure to closed position after the material has been discharged from the hopper and upon a second release of the latch member.

13. In a device of the character described including material handling hoppers having outlet openings, gate structures adapted to close said openings and movable to and from closed position by gravity, a latch member for each gate structure engageable with its respective gate structure to releasably hold it in either open or closed position, common means for effecting the release of the latch members, and means whereby either latch member may be released independently of the other upon actuation of said common means.
14. In testimony whereof I have hereunto affixed my signature.
